UNITED STATES PATENT OFFICE.

JAMES L. CRANDALL, OF MALDEN, MASSACHUSETTS, ASSIGNOR TO THE CRANDALL ENGINEERING COMPANY, OF BOSTON, MASSACHUSETTS, A CORPORATION OF MAINE.

RAILWAY DRY-DOCK.

1,293,046.

Specification of Letters Patent.

Patented Feb. 4, 1919.

Application filed April 17, 1918. Serial No. 229,215.

To all whom it may concern:

Be it known that I, JAMES L. CRANDALL, a citizen of the United States, and a resident of Malden, county of Middlesex, and 5 State of Massachusetts, have invented an Improvement in Railway Dry-Docks, of which the following is a specification.

My invention relates to railway dry docks or marine railways movably arranged on 10 ways, and has more particular reference to the means connected between the dock and the power actuated means employed to move the dock along its way.

It is common practice in railway dry 15 docks to employ a power driven shaft located at one extremity of travel of the dry dock, and to connect said shaft through a plurality of draw chains with the dry dock. The chains are commonly arranged to pass 20 over sprockets on the power driven shaft, and are connected to the dock through equalizing means which may be arranged in a draw head connected to the dock or incorporated into its structure. The rotation 25 of the driven shaft serves to wind the draw chains over sprockets fixed to the shaft and to thereby move the dock along the ways. There is designed to be no relative motion 30 between chains, but because of unavoidable slight inequalities in the length of the links composing the chains, a small amount of relative motion of the chains does take place, and the equalizing device associated with 35 the dry dock serves to distribute the load equally between all of the chains connected with the dock and with the power driven shaft.

The chains connected between the driven 40 shaft and the dry dock are commonly arranged in loops; that is, a chain passes over a sprocket on the driven shaft and around a pulley associated with the equalizing means arranged in the draw head of the dock and over another sprocket on the 45 driven shaft, thus forming a single loop between the driven shaft and the draw head. A sufficient number of such loops are arranged between the driven shaft and the draw head and between which, due to the 50 equalizing device, the load is equally distributed.

It sometimes happens, from various causes, that a chain forming a side of one

of the loops breaks; in which event, the load formerly taken by the loop must now 55 be taken by the other loops connected between the driven shaft and the dock.

The breakage of a chain forming one side of a loop throws that portion of the load which had been taken by both sides of the 60 loop on to the remaining loops; which loops will, in such case, be unduly loaded. The breaking of the chain forming one side of a loop serves to entirely destroy the loop, so far as its taking any stress is concerned, 65 even though the other side of the loop remains sound and unbroken; and the effect is thereby the same as though both sides of the loop had broken.

The object of my invention is in the provision of means whereby, upon the breakage of a chain comprising one side of a loop, the other side of the loop may continue to be operatively connected between the power 70 driven shaft and the dry dock and continue 75 to take a share of the load, and the load may be so distributed through the equalizing means that all the chains connected between the power driven shaft and the dock, including the chain forming a portion of 80 the broken loop, have equal stresses therein. With this arrangement, but one half the stress taken by the loop when entire, must be distributed to the remaining loops, instead of all the stress, as has heretofore 85 been the case. In such case, with a plurality of loops, the small added stress that each chain receives is usually insufficient to dangerously overload it.

The means I employ to accomplish the object of my invention is in the provision of stops attached to each side of the loop of chains and arranged on the chains but a small distance above the draw head. In the event of a chain breaking between the 90 power driven shaft and a stop, the slack chain between the stop and a solid portion of the draw head will be taken up or distributed through the equalizing means to all the other chains connected between the 95 power driven shaft and the draw head, and the chain comprising the other side of the loop will pull against the stop, and the stress taken by the broken loop will be distributed equally through the remaining 100 other side of the loop and the remaining 105

loop. The effect of the stop is as though the broken end of the chain is solidly connected, through the equalizer, with the draw head.

5 Figure 1 is a partial view of a railway dry dock and hauling mechanism, embodying my invention.

10 Fig. 2 is a partial side elevation of the railway dry dock and hauling mechanism, embodying my invention.

Fig. 3 is a plan view of a chain stop.

Fig. 4 is an elevation of a chain stop.

Fig. 5 is a front elevation of a hawse pipe.

15 Fig. 6 is a sectional view of the hawse pipe on the line 6—6 of Fig. 5.

Fig. 7 is a diagrammatic representation of the chains and draw head, with a chain broken.

20 Fig. 8 is a detail of a modified arrangement of hauling mechanism.

As here shown, an end of the railway dry dock, represented by 10, is provided with a draw head 11, which is connected thereto by the pins 12 and links 13, although the draw head may be otherwise connected to the dry dock. The draw head 11 rests upon a cradle 14, which is movably arranged on the ways 15, upon which the dock rests.

25 The draw head includes, at its portion thereof connected with the dock, two beams or girders 16, spaced apart to form a substantially box structure, and maintained in said relation by the pivot blocks 16' to which said girders are secured and through which 30 the drawing stresses are transmitted to the pins 12 and links 13. A number of pulleys 17 are arranged in the space between the girders 16, being preferably equally spaced from one another, and are rotatably mounted 35 on pins 17' fixed in the draw head 11.

40 A second box girder, formed of the girders 18, comprises the foremost part of the draw head, and is connected with the rear girders 16 by means of the short struts or 45 columns 19, which serve to maintain said girders 16 and 18 in spaced relation and also serve to take the stress that is arranged to fall upon the girders 18 when a chain is 50 broken, and a stop, to be hereinafter more fully described, is moved into engagement with said girders 18 to transmit the load from a broken loop to the remaining loops 55 of chains of the hauling mechanism. The means whereby the dry dock may be moved

60 along the ways 15 includes the shaft 20, disposed at the upper end of travel of the dock and which may be rotated by any suitable means, not necessarily shown. A number of sprockets 21 are fixed on said shaft in suitable spaced relation, and a number of chains, each arranged to form a loop comprising the sides 23, and are passed around said sprockets and extend to the draw head. The chains forming loops 23 are passed through 65 openings 36 in hawse pipes 24 secured be-

tween the spaced apart girders 18 in the fore-part of the draw head, and the loop is passed around pulleys 27, which are pivotally connected to links 26. Other pulleys 25 are pivoted to the other ends of said links 26. 70

A chain 28 is arranged with the ends 30 thereof secured to and between the girders 16 adjacent the ends thereof, and is looped alternately around the pulleys 27 secured to the links 26 and the fixed pulleys 17, pivotally mounted between the girder 16 in the rear part of the draw head structure. 75

Said chain 28 comprises what is termed a bridle upon which the pull of the draw chains is taken. By arranging the chain 28 alternately between the pulleys 25, connected through the links 26 and pulleys 27 to the loops of the draw chain, and pulleys 17 pivoted between the girders 16, the stresses of the draw chains comprising the separate 80 loops may be equalized; for if one loop has a tendency to shorten faster than other loops, due to inequalities in the lengths of the links forming the chains, then said loop will tend to pull up on that portion of the bridle 85 chain wound over its pulley 25, which pull will be resisted equally by all of the other loops of the draw chains; and consequently each loop, or the chain included in the sides 23 and 23 thereof, may be stressed equally 90 at all times.

The stop incorporating my invention and as shown in detail in Figs. 3 and 4, may comprise two bars 31 and 32, having grooves 33 therein arranged to receive a link 34 of the chain 23 which is adapted to be clamped between said bars 31 and 32 by bolts 35. The bars 31 and 32 are of such a width that they are prevented from entering the opening 36 in the hawse pipe 24; and, therefore, upon 100 the breaking of a chain between a stop and the power driven shaft, that portion of the chain between a stop and the pulley 27 will be drawn into the draw head until the stop comes into engagement with the outer face 110 of the hawse pipe 24, and further movement of the chain is thereby prevented.

The stop may be of any other special or desired shape, as its function is to prevent the chain, when it becomes broken, from being drawn through the opening in the hawse pipe and from around its pulley 27, and to operably secure the broken end to the draw head. 115

The position of the clamp 31 upon the 120 draw chains may be varied within comparatively wide limits; but it is advisable to position the clamps as close to the draw head as possible, leaving only sufficient space therebetween to provide for relative movement of the two portions of a loop, due to the inequalities in length of the links comprising the chains, such that in the normal operation of the chains in moving the dock along the ways, the stops will not come into 125 130

contact with the cross head. Upon the breakage of the chain, however, between the stop and the power driven shaft, the stop should be sufficiently close to the draw head that 5 there is but small rearward movement of the link 26, upon which are pivoted the pulleys 25 and 27; so that the loop in the bridle chain 28 around the pulley 17 is not entirely straightened.

10 Upon the breakage of a chain composing a side of a loop, the strain is consequently relieved from one of the loops of the bridle chain 28, and consequently the dock begins to slip back and the chains continue to wind 15 up until all of the slack has been taken by the remaining loops in the draw chains. The stop on that portion of the chain which is broken comes in contact with the hawse pipe secured in the front end of the draw bar, 20 or to the front girders 18 of the draw head, and further movement of the chain is thereby prevented. This condition is diagrammatically illustrated in Fig. 7. The total 25 load of the dock is now taken up by all of the remaining loops of chains, and by the remaining unbroken side of the ruptured loop.

In the illustration shown in Fig. 1, if one of the ten reaches of chain, forming the five 30 loops extending between the driven shaft 20 and the draw head breaks, there remain nine reaches of chain between which the load is equally distributed. The effect of the stop on the broken end of one of the chains is 35 as though the end of the chain were secured directly to the draw head. The load of the dry dock is now equally divided between the remaining reaches of chain, as all of the load is transmitted to the dock structure through 40 the bridle chain 28, as before, and the breaking of the chain comprising a side of a loop results in the loss of but one side of a loop instead of the entire loop, as heretofore.

Although I have described and shown the 45 reaches of chain as being connected in loops and passed over pulleys yet the reaches of chain may be otherwise arranged to serve the same purpose.

The pulleys may be considered, in effect, 50 as continuous levers, and where the relative motion between the two reaches of chains comprising a loop is but slight, then the pulleys may be replaced by actual levers.

Such an arrangement is shown in Fig. 8, 55 in which the pulleys 25 and 27 connected by the link 26 are replaced by the whiffle trees 60 and 61, with the reaches 62—62 of chain wound over the driving shaft connected to the ends of the whiffle tree 60, and the whiffle 60 tree 61 connected through chains 63—63 to the ends of separate whiffle trees 64 pivoted at their central points to the frame of the draw head.

The whiffle trees 61 and 64, connected 65 through the chains 63 are in effect the equiv-

alent of the bridle chain 28 passed over the pulleys 17 pivoted to the draw head or dock structure.

As before, stops may be arranged on the reaches of chain to operably connect the un- 70 broken reach of chain, though a whiffle tree 60, with the draw head, upon the breaking of the other reach of chain completing the loop; or stops or abutments 65 may be secured to a member 66 of the draw head or 75 dock structure adjacent the ends of the whiffle trees 60 which, upon the breaking of a reach of chain, serve to connect the other reach of chain, through the whiffle tree with the draw head or dock structure, these, in 80 effect, acting in all respects, similar to the stops arranged upon the reaches of chain.

I claim:—

1. In combination with a railway dry dock movably arranged on ways, and a hauling 85 device to move said dock along the ways, of a plurality of draw chains extended in loops between said device and the dock, an equalizing device associated with the dock, the chains comprising the sides of a loop being 90 connected through the loop to the equalizing device, and means to transfer the load of a chain comprising a side of a loop to the other side of the loop and to the other loops 95 of chains upon the breaking of said chain.

2. In combination with a railway dry dock movably arranged on ways, and a hauling device to move said dock along the ways, of a plurality of draw chains extended in loops 100 between the device and the dock, an equalizing device associated with the dock, said loops of chains being connected through the loops with the equalizing device to thereby equalize the load on the chains, and a chain stop associated with the chains adjacent the dock and operable to connect one side of a loop through the equalizing device to the dock upon the breaking of the chain comprising the other side of the loop 105 to thereby distribute the load taken by the broken chain to the other side of the loop and the other loops.

3. In combination with a railway dry dock movably arranged on ways, and a hauling 115 device to move said dock along the ways, of a plurality of draw chains extended in loops between the hauling device and the dock, an equalizing device associated with the loops of chains and the dock, the chains comprising a loop being connected through 120 the loop and the equalizing device with the dock and adapted for relative movement, and a chain stop on the chains adjacent the dock and operable upon the breaking of a chain comprising one side of a loop to connect the other side of the loop to the dock and distribute the load taken by the broken chain to the other side of the loop and the other loops.

4. In combination with a railway dry 130

dock movably arranged on ways, and a hauling device to move said dock on the ways, of a draw head associated with the dock, a plurality of loops of draw chains connected to said device and through equalizing means with the draw head, and chain stops secured to said chains adjacent the draw head movable into engagement with the draw head, upon the breaking of the side of a loop 10 to distribute the pull of that side of the loop

between the other side of the loop and the other loops.

In testimony whereof, I have signed my name to this specification, in the presence of two subscribing witnesses.

JAMES L. CRANDALL.
